Albert M. Austin
ATTORNEY

UNITED STATES PATENT OFFICE.

CHARLES N. CORYELL, OF MAMARONECK, NEW YORK, ASSIGNOR TO SCOVILL MANUFACTURING COMPANY, OF WATERBURY, CONNECTICUT, A CORPORATION OF CONNECTICUT.

VANITY CASE.

Application filed May 27, 1925 Serial No. 33,111.

Special objects of this invention are to provide a vanity case of compact form and appearance but adapted to carry an ample supply of powder with the puff and mirror or other articles usually associated in such a case.

These objects are attained in part by constructing the case with a curved or convex bottom and top and by providing the powder 10 compact with a holder to fit the interiorly concaved shape of the case. The curvature of the top and bottom stiffens these walls and at the same time makes the box appear thinner than a cylindrical box of uniform thickness 15 throughout, while the formation of the compact with a back fitting in the box provides a maximum of powder within a minimum of space and provides a substantially flat exposed face for convenient use. The compacts 20 are conveniently formed in this shape by molding them while plastic into saucer-shaped holders or supports shaped to fit the concavity of the box and adapted to be held in place therein.

25 Various other objects and advantages of the invention will be obvious from the following particular description of one form of device embodying my invention or from an inspection of the accompanying drawings; and the invention also consists in certain new and novel features of construction and combinations of parts hereinafter set forth and claimed.

In the drawing accompanying and forming part of this specification, one of the simple, practical embodiments of the invention is illustrated, Figure 1 being a perspective view of the case in opened condition, Figure 2 being a cross sectional view of the case in closed condition, and Figure 3 being a detached broken side view of one of the compacts. Figure 4 is a sectional view of the hinge structure as on substantially the plane of line 4—4 of Figure 2.

45 The top 5 and bottom 6 of the case illustrated comprise a convexed outer portion and a flat central portion and provide by their shape a box which is deeper at the center and thinner at the edges. The general appearance is that of a box considerably thinner than a cylindrical box of uniform thickness throughout. These cases are usually made

of sheet metal and the rounding out of the top and bottom stiffens these walls sufficiently to enable a relatively light, inexpensive and 55 easily worked grade of sheet metal to be used.

The powder compact 7 is shown formed with a back curved to substantially fit the bottom and has a substantially flat face providing a usable surface of the full diameter of the compact. This special compact is conveniently produced by molding the same in a saucer-like holder or support 8 having a convexity substantially conforming to the 60 concavity of the bottom and affording a backing by which the compact may be handled and be held within the case.

In the particular embodiment herein disclosed, the edges of the compact holder have 70 a frictional engagement within the rim of the bottom, which rim is shown as provided by an upstanding ring 9 frictionally held in the beaded edge 10 of the bottom. This ring serves also, in the illustration, as a retainer 75 for the hinge which connects the two main parts of the case. This hinge is shown as made up of a loop 11 fitting in a cut away portion 12 of the bead in the lower section and having a hinge wire 13 extending through 80 it and engaged within the curl of the bead at opposite sides of the recess 12.

After the hinge wire is extended through the loop so that it projects at both ends, it will be seen that the hinge can be assembled 85 by placing the loop within the recess so that the projecting portions of the hinge wire seat within the bead, the retainer ring being then forced to its seat within the bead, into position over the hinge loop and the projecting 90 portions of the wire. The ring may be formed with a slight offset 14 where it engages over the loop and wire ends so as to interlock over such parts and this inward depression in the ring may serve as a catch 95 for engagement by the rim of the compact backing, Figure 2, and so act as a retainer for the compact.

The top or cover section is shown as having a circular bead 15 matching the bead of the other section and as having an integral rim 16 extended therefrom and engaging over the upstanding rim of the lower section. The engagement of this flange over the rim pro-

vides sufficient friction to hold the parts in closed relation and the circular beads add to the ornamental appearance of the case and provide annular grips, facilitating the opening and closing of the case.

In the present embodiment of the invention, where only the one compact is provided, a mirror 17 or other toilet article may be mounted in the top of the case, said mirror 10 being shown as held in place by a confining ring 18 frictionally engaged within the flanged rim of the top.

This improved case is of simple, inexpensive construction, easily assembled, is attractive looking and because of its symmetrical form and reduced thickness at the edges, has the appearance of being much smaller than it actually is. The powder compacts, because of their novel form, occupy a maximum of 15 the available space within the case, provide a wide flat exposed surface for convenient use and can be inexpensively produced by simply molding them in the shallow saucer-like supports. The upstanding rim of the bottom section provides a shallow compartment for a powder puff which, as shown at 19, may be of 20 conveniently large size, equal to the full internal diameter of the case. The saucer-like backing of the compact may be inexpensively 25 produced in suitable metal.

While I have shown and described and have pointed out in the annexed claims certain novel features of my invention, it will be understood that various omissions, substitutions and changes in the forms and details of the device illustrated and in its operation 30 may be made by those skilled in the art without departing from the spirit of my invention.

What is claimed is:

1. A toilet case having bottom and top comprising a convexed portion and a flat central portion whereby its thickness at the perimeter is less than at the center, and a cylindrical side wall in combination with a toilet compact having a convex bottom and substantial-

ly flat exposed face securely held in the concave shaped interior of the box.

2. A toilet case comprising hinged sections, each having an interiorly concave shape in combination with a toilet compact having a substantially flat exposed face, mounted on a flexible metallic backing of greater diameter than the compact and sprung into said box, one of the sections having an upstanding annular rim engaged by the backing whereby the compact is frictionally retained in place.

3. A toilet case comprising hinged sections, each having an interiorly concave shape in combination with a toilet compact having a substantially flat exposed face, mounted on a flexible metallic backing of greater diameter than the compact and sprung into said box, both of the sections having an upstanding annular rim overlapping when the case is closed, one of said rims being engaged by the backing to hold said compact in place.

4. A toilet case comprising detachably hinged sections having an interiorly concave shape in combination with a toilet compact having a substantially flat exposed face, mounted on a metallic backing of greater diameter than the compact and seating in said box, both of the sections having an upstanding annular rim overlapping when the case is closed, one of said rims being engaged by the backing to hold said compact in place, said rims co-acting to hold the case sections in hinged relation when the rims are in place.

5. A vanity case comprising a casing section having a rim, and provided with a hinge part, a second section having a hinge part cooperating with said first hinge part, a ring member fitting in said rim having an offset portion to accommodate one of said hinge parts, and a toilet article in said casing section engaged under said offset portion.

In testimony whereof I have hereunto set my hand.

CHARLES N. CORYELL.
